NURSERY UTILITY BAG

Alexander Miner, New York, N. Y.

Application May 19, 1954, Serial No. 30,567

Term of patent 7 years

(Cl. D87—3)

FIG.1

FIG.2

FIG.3

To all whom it may concern:

Be it known that I, Alexander Miner, a citizen of the United States, residing in the city of New York, county of New York, and State of New York, have invented a new, original, and ornamental Design for a Nursery Utility Bag, of which the following is a specification, reference being had to the accompanying drawing, forming part hereof, in which:

Fig. 1 is a view in elevation of a nursery utility bag showing my new design;

Fig. 2 is a top plan view with a portion of the handle broken away for purpose of illustration; and

Fig. 3 is an end elevation with a portion of the handle broken away for purpose of illustration.

I claim:

The ornamental design for a nursery utility bag, as shown and described.
